[57] **CLAIM**

The ornamental design for a cartridge for a lateral anastomosis surgical stapler, substantially as shown and described.

DESCRIPTION

FIG. 1 is a perspective view of a cartridge for a lateral anastomosis surgical stapler showing my new design; FIG. 2 is a side elevational view thereof;

FIG. 3 is a top plan view as seen from FIG. 2; FIG. 4 is a bottom plan view as seen from FIG. 1; FIG. 5 is an enlarged view of a portion of the left hand portion of FIG. 4;

FIG. 6 is an end elevational view as seen from the left of FIG. 2; and

FIG. 7 is an end elevational view as seen from the right of FIG. 2.

Fig. 2.

Fig. 3.

Fig. 4.
